UNITED STATES PATENT OFFICE.

JOHN OGDEN, OF CARDINGTON, PENNSYLVANIA.

DESIGN FOR A RADIATOR.

46,180.

Specification for Design.

Patented July 28, 1914.

Application filed May 26, 1914. Serial No. 841,162. Term of patent 14 years.

To all whom it may concern:

Be it known that I, JOHN OGDEN, a citizen of the United States, residing at Cardington, in the county of Delaware and State of Pennsylvania, have invented a new, original, and ornamental Design for Radiators, of which the following is a specification, reference being had to the accompanying drawing, forming part thereof.

The figure is a perspective view of the radiator, showing my new design.

I claim:

The ornamental design for a radiator, as shown.

JOHN OGDEN.

Witnesses:

L. C. HOOPES,
CHAS. N. VALENTINE.
